UNITED STATES PATENT OFFICE.

HERBERT S. BLYNT, OF BINGHAMTON, NEW YORK.

DESIGN FOR A TREAD FOR AN AUTOMOBILE-TIRE.

50,644.

Specification for Design.

Patented Apr. 24, 1917.

Application filed February 5, 1917. Serial No. 146,853. Term of patent 14 years.

To all whom it may concern:

Be it known that I, HERBERT S. BLYNT, a citizen of the United States, residing at Binghamton, in the county of Broome and State of New York, have invented a new, original, and ornamental Design for Treads for Automobile-Tires, of which the following is a specification, reference being had to the accompanying drawing, forming part thereof.

Figure 1 is a perspective view of a portion of a tire showing the design;

Fig. 2 is a face view of the tread of a tire showing the design.

I claim:

The ornamental design for a tread for an automobile tire, as shown.

HERBERT S. BLYNT.
